CHARLES S. WILLIAMS, OF KINGSTON, PENNSYLVANIA, ASSIGNOR TO ELECTRIC SERVICE SUPPLIES COMPANY, OF PHILADELPHIA, PENNSYLVANIA, A CORPORATION OF PENNSYLVANIA

TRAIN CONTROL

Application filed August 31, 1928. Serial No. 303,134.

This invention relates to automatic train control systems, and more particularly to improvements therein for rendering it impossible to obtain a false signal indicating a clear condition when the train is operating in restricted or occupied territory.

Heretofore and prior to this invention considerable difficulty has been experienced in connection with automatic train control systems in that an occasional false signal would be obtained by the engineman indicating a clear condition ahead when, in fact, the contrary was true. Needless to say, the danger of such a situation was immediately appreciated by those familiar with automatic train control operation and every effort was made to obviate this possibility of obtaining a signal which falsely indicated a clear track while the train actually was operating in restricted or occupied territory. To these men skilled in the art it was as difficult to advance a reason for this dangerous condition as it was to apply a remedy and until the present invention the problem has remained unsolved, although various expedients have been tried from time to time without any noticeable success.

I have discovered that the cause of this condition lay not in the trackway systems or circuits now in more or less general use, nor in the locomotive circuit to which energy is supplied by the locomotive headlight generator, but rather in the generator itself. One of the greatest difficulties encountered in the use of electric generators as heretofore designed is in connection with leaking currents, such as are due to failure of armature insulation and grounding of one or more of the current generating coils. As will be more fully explained hereinafter, where the generator is used in the locomotive circuit of a train control system the grounding of one or more of the armature coils results in the establishment of a superimposed alternating current which enters the amplifier of the circuit and so energizes the train control relay with the result that there is obtained a false clear condition.

It is accordingly among the objects of this invention to overcome the aforementioned

difficulties by employing as the source of energy supply for the locomotive circuit of a train control system an electric generator which is so designed as to effectually preclude the possibility of one or more of the armature or current generating coils being grounded through the housing, shaft or other metallic parts of the generator.

A further object of the invention is the provision in the locomotive circuit of a train control system of a generator the armature of which is electrically insulated from its shaft and from adjacent metallic parts of the generator whereby to prevent the generation of stray currents due to a grounded armature and so avoid the danger of obtaining a false traffic signal.

Other objects of the invention will appear more fully hereinafter.

The invention consists substantially in the combination, construction, location and relative arrangement of parts, all as will be described more fully hereinafter, as shown in the accompanying drawings, and as finally pointed out in the appended claims. For purposes of illustration, I have shown the invention as applied to the locomotive circuit of a particular type of automatic train control system, but it will be understood, of course, that the invention is equally applicable to locomotive circuits of systems other than that shown herein for purposes of illustration.

In the accompanying drawings:

Figure 1 is a diagrammatic view showing a typical track circuit for a two-speed, continuous, inductive, automatic train control system;

Figure 2 is a diagrammatic view showing a typical locomotive circuit for use in connection with the track circuit shown in Figure 1, one of the current generating coils of the armature being shown grounded; and

Figure 3 is a longitudinal section through one form of insulated armature mounting.

In order that a better understanding may be had of the present invention, it has been deemed advisable to first describe briefly the operation of the typical wayside circuit shown in Figure 1. It will be noted that the

track 10 is divided into a series of blocks including the home or occupied block 11, the caution blocks 12 and 13 and the clear blocks 14 and 14'. In the following description it will be understood that the locomotive 15 is traveling in the direction of the arrow, that is, from right to left. Paralleling the track 10 is the transmission line 16 from which alternating current is supplied to the exit ends of each of the blocks 12, 13, 14 and 14' through the circuits 17, 18, 19 and 19', each of which latter circuits includes a line transformer, a track transformer, and a battery connected in series with the secondary of the track transformer. Connected across the tracks of each block at the entrance end thereof is a direct current track relay, it being noted that this track relay for any particular block is connected in series with the secondary of the track transformer for that block. It will thus be evident that each block is a complete circuit in itself to which both alternating and direct current is supplied, the former being supplied from the transmission line 16 and the latter from the battery.

As clearly appears in Figure 1, the signal 24a for the block 11 indicates danger or an occupied block, this because of the fact that the locomotive 15 has shunted the rails of this block thereby preventing any alternating or direct current from flowing between the rear end of the locomotive and the signal 24a. In consequence of this, the track relay 23a for the occupied block 11 has become deenergized and so has permitted the contact fingers (designated generally by the numeral 25a) to drop into the position shown in Diagram A of Figure 1. Inasmuch as both the upper and lower quadrants of the signal 24a are controlled by these contact fingers, the dropping of the latter causes both arms of the signal to assume the upright position indicating danger or an occupied block.

Simultaneously as the track relay 23a is deenergized, the relay 26 is also deenergized (due to the opening of the lowermost contact 25a), thereby opening, as at 28, the circuit of the secondary of the line transformer 20a. The alternating current supply to the block 12, through the circuit 17, is thus interrupted. This block 12 is, however, supplied with direct current from the battery source 22a, which latter is connected in series with the secondary of the track transformer 21a. This direct current is sufficient to energize the track relay 23b connected across the rails of block 12, with the result that the contact fingers 25b (see Diagram B) are raised into the position shown. This completes the circuit to the operating mechanism for the upper quadrant of the caution signal 24b for block 12, causing the corresponding arm to be held at an angle. Inasmuch as the operating circuits for the respective signals are of the usual character and do not form an essential part

of the present invention, they have not been described in detail herein.

Movement of the upper arm of signal 24b into the inclined position causes its associated contact arms to shift from the vertical positions shown in Diagram A to the inclined positions shown in Diagram B, thereby completing the energizing circuit for the relay 32. This relay 32 is energized by the battery 60b of Diagram B, the circuit therefor being traced as follows:—from lower terminal of battery 60b through wires 61, 62, 63, relay 32 and wire 64 to the upper terminal of battery 60b. Due to the fact that the relay 26 remains deenergized, the relay 29 is deenergized with the result that the lower quadrant of signal 24b remains in upright position. The signal 24b thus indicates caution for the block 12.

Deenergization of the relay 30 opens, as at 31, the circuit of the secondary of the line transformer 20b with the result that the alternating current supply to the block 13 is interrupted. This block 13 is, however, supplied with direct current from the battery source 22b, which latter is connected in series with the secondary of the track transformer 21b. This direct current is sufficient to energize the track relay 23c connected across the rails of block 13, with the result that the contact fingers 25c (see Diagram C) are raised into the position shown. This completes the circuit to the operating mechanism for the upper quadrant of the caution signal 24c for block 13, causing the corresponding arm to be held at an angle. The lower quadrant remains in the upright position, however, this being due to the fact that relay 34 remains deenergized so long as the contacts 27b are open through the deenergization of the relay 30, the latter being in circuit with the battery 60a of Diagram A. The current for energizing the relay 34 is derived from the battery 60b.

Energization of the track relay 23c for block 13 also effects the closing of the lowermost contact 25c (see Diagram C), thereby causing the relay 32 to become energized. Energization of the relay 32 effects the closing, as at 33, of the secondary circuit of the line transformer 20c, thereby sending alternating current through the rails of block 14 by way of the circuit 19. It will be noted that, as in the case of block 13, the direct current track relay 23d for block 14 is energized from the battery 22c connected in series with the secondary of track transformer 21c at the exit end of block 14. (See Diagram C.) Due to the closing of contacts 27d through the energization of the last mentioned track relay 23d, the relay 32' is energized, thereby causing the contacts 33' to close. The relay 32' is in circuit with the battery 60c of Diagram C. Alternating current is then supplied to the rails of block 14' 130

through the circuit designated by the numeral 19'. (See Diagram D.)

With contacts 27c closed by action of the relay 32, the relay 34' becomes energized by current supplied from battery 60c and in so doing energizes the operating mechanism for the lower quadrant of the signal 24d for block 14. The result is that the lower arm of the signal is held in the inclined position shown. The upper quadrant of this signal is also held in the inclined position through the action of the track relay 23d upon the contact fingers 25d, it being understood that when both arms of the signal 24d are inclined in this manner, the indication is that the block ahead is clear of all traffic.

With the blocks 11, 12, 13 and 14 maintaining the prevailing conditions shown in Figure 1, and assuming the entrance of a train into block 14, the signal in the locomotive cab should remain green or clear and it should be possible for the train to run at any desired speed until it reaches the first caution block 13. Immediately upon entering this caution block, the cab indication should change from green or clear to yellow or caution, this change in the cab signal being effected by reason of the fact that there is no alternating current flowing in the caution block. It will be remembered, as explained hereinbefore, that the alternating current supply is opened to all but the clear blocks.

Referring now to Figure 2 showing a typical locomotive circuit for use in connection with the wayside circuit briefly described hereinbefore, it will be observed that the energy for the dynamotor 35 is furnished by the locomotive headlight generator, designated generally by the numeral 36. The dynamotor 35 is employed for supplying energy to the plate circuit of the amplifier 37, the energy for the amplifier tube filaments being supplied by the generator 36. Suitably carried by the locomotive is a receiver 38 comprising the pick-up coils 39 and the laminated steel bar 40 grounded to the locomotive. The bar 40 and the pick-up coils form, in effect, a capacitive condenser through which the latter are grounded to the locomotive.

The receiver coils are suitably connected to the input side of the amplifier 37 so that when alternating current is flowing in the rails and a voltage is induced in the receiver coils above them, alternating current is caused to flow through the primary of the output transformer 41. In usual practice, it is customary to enclose the wires leading from the receiver to the amplifier in a conduit 42 which is grounded to the locomotive, thereby creating a capacitive coupling through which the conduit-enclosed wires are grounded.

The alternating current delivered by the transformer 41 in response to energization of

the track receiver is rectified by a static rectifier 43, and the direct current thus obtained is employed to energize the direct current train control relay 44. Assuming the locomotive to be traveling in unrestricted territory, that is, in a clear block, the alternating current flowing in the rails thereof will be picked up by the receiver 38 for energization of the train control relay 44. When the latter is so energized, the contacts 45 are raised to the position shown in Figure 2, with the result that energy is supplied from the generator 36 to the green or clear signal 46 in the locomotive cab.

When the train enters a restricted block, either caution or occupied, the relay 44 is de-energized, due to the fact that there is no alternating current flowing in the rails of the restricted block, with the result that the contacts 45 drop into the dotted position. Energy is then supplied from the generator to the yellow or caution signal 47 and to the signal bell 48, notifying the engineman that he is in restricted or dangerous territory. The foregoing describes the operation of the locomotive circuit with all of the appurtenant apparatus functioning properly.

Let us assume, however, that one of the armature coils becomes grounded, as at 49 in Figure 2. An alternating current is immediately established which flows (as indicated by arrows) from the grounded armature coil to the grounded conduit 42 or the grounded receiver 38. This superimposed alternating current passes through the primary of the transformer 41. An alternating current is thus delivered by the transformer which is rectified by the rectifier 43 for energization of the train control relay 44. The result is that the contacts 45 are raised to the full line position shown in Figure 2 with the consequence that a green or clear light indication 46 is obtained. It will be observed that this indication is obtained independently of any voltage induced in the receiver 38 and irrespective of whether or not alternating current is flowing in the rails. Obviously, the train control relay 44 should never be energized except by the voltage induced in the receiver as the locomotive travels over a block in the rails of which alternating current is flowing. As has been explained hereinbefore, there is no alternating current flow in the caution or occupied blocks.

To avoid the above described possibility of obtaining a false clear signal when the train is really operating in restricted territory, such as caution or occupied blocks, this invention contemplates the use of a generator 125 the armature coil mounting of which is insulated from the shaft and all other metallic parts. Preferably, the commutator is likewise insulated from the shaft and other metal parts of the generator frame. In Figure 4 130

there has been shown one form of motor for the generator, it being observed that the armature coil mounting or core 50 is insulated from the shaft 51 by the insulating sleeve or bushing 52. The commutator 53 is also insulated from the shaft by a similar insulating sleeve or bushing 54. The ends of the coil mounting are covered by insulating disks 55 and those of the commutator by the insulating disks 56. The use of a generator embodying an insulated armature unit constructed along the lines shown in Figure 3 effectually precludes the possibility of grounding of one or more of the current generating coils through the housing or other metallic parts of the generator and thereby prevents the generation of that superimposed alternating current which operates to create a false clear condition when the train is traveling in caution or occupied blocks.

Although the present invention has been described in connection with a rather specific system of automatic train control, it will be understood, of course, that the present invention is applicable to many other train control systems, and, therefore, should not be limited in scope to the particular system shown except as indicated by the appended claims.

What is claimed as new and useful is:

- 30 1. In an automatic train control locomotive circuit, in combination, a direct current generator, an amplifier circuit having an output transformer, an alternating current receiver included in said amplifier circuit for energizing the primary of said transformer, said receiver being grounded through a capacitive condenser, and means for insulating the armature of said generator against the grounding of one or more of the current generating coils thereof whereby to effectually preclude the generation of an alternating current which flows between said grounded coil and said grounded receiver through the primary of said transformer.
- 45 2. In the locomotive circuit of an automatic train control system, in combination, an amplifier circuit including an output transformer, a train control relay energizable from the secondary of said transformer, an alternating current pick-up coil included in said amplifier circuit for energizing the primary of said transformer, said pick-up coil being grounded, and a generator for supplying energy to the amplifier, the armature of said generator being insulated against the grounding of one or more of the current generating coils thereof whereby to prevent the passage of alternating current from a grounded current generating coil to the grounded pick-up coil through the primary of said transformer and thus obtain an undesired energization of said train control relay.
- 60 3. In an automatic train signal circuit, in combination, a direct current generator, an amplifier circuit the output of which is con-

nected to a relay controlling the operation of signal devices, a current receiver included in said amplifier circuit for energizing said relay, and means for insulating the armature of said generator against the grounding of one or more of the current generating coils thereof whereby to effectually preclude the establishment of an undesired current flow between said grounded coil or coils and a ground located at the receiver side of the amplifier circuit.

In testimony whereof, I have hereunto affixed my signature.

CHARLES S. WILLIAMS.
